ISAAC C. WILLIAMS, OF PHILADELPHIA, PENNSYLVANIA.

Letters Patent No. 70,306, dated October 29, 1867.

IMPROVED LAY-AWAY VAT FOR TANNING.

The Schedule referred to in these Letters Patent and making part of the same.

TO ALL WHOM IT MAY CONCERN:

Be it known that I, ISAAC C. WILLIAMS, of the city of Philadelphia, in the State of Pennsylvania, have invented a new and useful Improvement in the "Lay-Away" Vat for Tanning; and I do hereby declare that the following is a full, clear, and exact description of the construction and operation of the same, reference being had to the accompanying drawings, making a part of this specification, in which—

Figure 1 is a plane view of the said improved vat, and

Figure 2 a vertical transverse section of the same on the dotted line $x y$ of fig. 1—

Like letters of reference indicating the same parts when in both figures.

The object of my improvement is to obviate the necessity of removing the hides in a "lay-away" vat when a renewal of the tanning liquor is required; and the nature of my invention consists, substantially as herein-after described, in providing the interior of the vat with an inclined supplementary bottom, one or more pairs of detachable hide-supporting frames, and interstitial supplementary sides and ends, so constructed and applied that all the tanning liquor can be quickly and thoroughly withdrawn from between the hides, and fresh liquor replaced, as often as may be required, without removing or handling any of the said hides, and without diminishing the advantages peculiar to the "lay-away" vats.

Referring to the drawings, A B is the vat, C the inclined supplementary bottom, D D a pair of the detachable hide-supporting frames, and E E E E the interstitial supplementary sides and ends. The body of the vat A B is made in the usual rectangular form, and provided with a draining-hole and plug for the discharge of the spent liquor. The interstitial sides and ends E consist of narrow wooden slats, $e' e'$, nailed fast to horizontal pieces, $e'' e''$, in vertical positions, parallel with each other, and at a quarter of an inch apart, (more or less,) entirely around the inner sides and ends of the body A B, substantially as represented in the drawings, thus producing a clear space behind the slats communicating with the interior of the vat. The inclined supplementary bottom C is permanently fixed at a short distance above the usual bottom b' of the vat, and is inclined downward from both sides of its longitudinal centre or middle to the interstitial sides E of the vat, (see fig. 2.) The detachable hide-supporting frames D D are two separate skeleton frames, extending horizontally from end to end of the vat, at about half the height of the same, (in this instance,) and with their two inner-side edges abutting together along the same, and the two frames inclining downward therefrom (like the supplementary bottom C) to the sides of the vat, and resting upon cleats $e''' e'''$, nailed firmly to the slats e' , (see fig. 2.) These frames are for the purpose of dividing the weight or pressure of the mass of hides in the vat.

Operation.

The frames D D being first taken out of the vat A B, the hides to be tanned are successively laid alternately upon the two inclined surfaces of the supplementary bottom C, with the straight edges of the said hides next to the interstitial sides E, and their irregular or ragged edges interlapping with each other over the central ridge formed by the said inclined bottom C, until the layers, with ground bark sprinkled between, as heretofore, reach the cleats e''' , when the pair of detached frames D D is replaced upon the said cleats, and the "laying away" of the hides and bark continued thereon, in the same manner, until the vat is fully supplied. The plug a' is then inserted in the draining-hole, and the fresh tanning liquor run into the vat until the hides are perfectly covered thereby. When a substitution of fresh for the exhausted tanning liquor is required, the plug a' is withdrawn, and the exhausted liquor then immediately runs off, and drains away completely from between the hides by running down their inclined surfaces, and between the slats e' to the space and outlet below the supplementary bottom C, after which the plug a' is to be reinserted, and the fresh liquor run into the vat as before, thus, it will be seen, rendering the tedious and laborious removal or "handling" of the hides, for the purpose as heretofore required in lay-away vats, entirely unnecessary until after the tanning is completed.

I am aware that the hides have been suspended vertically in vats so as to allow the requisite changings of the liquor without removing the hides, but this mode does not admit of the intervention of tan between the hides to keep them from direct and close contact with each other, nor of the introduction of so large a quantity of the hides in the same-sized vat as in the lay-away system; therefore I do not desire to claim broadly the doing away with the necessity of removing or handling the hides in changing the liquor, nor do I intend to confine myself to the use of a single pair of the frames D D, as the number should be increased in proportion to the

depth of the vat; but, having fully described my improvement in the lay-away vat, what I claim as new therin of my invention, and desire to secure by Letters Patent, is confined to the following, viz:

1. I claim the employment of the interstitial supplementary sides and ends E, substantially as described, for the purpose of allowing a more free and perfect escape of the spent liquor, and the admittance of the fresh, as described.

2. I claim the application of the supplementary inclined bottom C, substantially as described, for the purpose of causing the spent liquor to run off from between the hides in a perfect and rapid manner.

3. I also claim the employment of the skeleton frames D D, or their equivalents, substantially as described, for the purpose of preventing too great a pressure between the layers of hides.

ISAAC C. WILLIAMS.
